[57] CLAIM

The ornamental design for an automobile roof sign, as shown and described.

DESCRIPTION

FIG. 1 is a perspective view of an automobile roof sign showing our new design;

FIG. 2 is a top plan view thereof, with the bottom being flat and ornamented;

FIG. 3 is a front elevational view thereof, with the rear being the same except flat;

FIG. 4 is a right side elevational view thereof, with the left side being a mirror image;

FIG. 5 is a perspective view of a second embodiment thereof; and wherein the only difference resides in the extension brackets; and,

FIG. 6 is a right side elevational view thereof, with the left side being a mirror image.

FIG. 4

FIG.3

FIG. 2

FIG. 1

FIG. 5

FIG. 6
